US00D929735S

(12) **United States Design Patent** (10) **Patent No.:** **US D929,735 S**
(45) **Date of Patent:** **** Sep. 7, 2021**

(54) **TRAVEL CASE FOR A DEVICE**

(71) Applicant: **Nicoventures Trading Limited**,
London (GB)

(72) Inventors: **Anthony Cruice**, London (GB);
Ainsley Cox, London (GB)

(73) Assignee: **Nicoventures Trading Limited**,
London (GB)

(**) Term: **15 Years**

(21) Appl. No.: **29/718,106**

(22) Filed: **Dec. 20, 2019**

(30) **Foreign Application Priority Data**

Jun. 21, 2019 (EM) 006590733
Aug. 8, 2019 (EM) 006691721

(51) **LOC (13) Cl.** **03-01**

Pedersen, P.A.

(57) **CLAIM**

We claim the ornamental design for a travel case for a device, as shown.

DESCRIPTION

FIG. 1 is a bottom and front perspective view of a travel case for a device.

FIG. 2 is a front elevational view of the travel case for a device depicted in FIG. 1.

FIG. 3 is a rear elevational view of the travel case for a device depicted in FIG. 1.

FIG. 4 is a bottom plan view of the travel case for a device depicted in FIG. 1.

FIG. 5 is a top plan view of the travel case for a device depicted in FIG. 1.

FIG. 6 is a left side elevational view of the travel case for a device depicted in FIG. 1.

FIG. 7 is a right side elevational view of the travel case for a device depicted in FIG. 1; and,

FIG. 8 is a top perspective view of the travel case for a device depicted in FIG. 1 in an alternate open position.

1 Claim, 7 Drawing Sheets
